(57) **CLAIM**

The ornamental design for a dosage dispenser, as shown and described.

DESCRIPTION

FIG. 1 is a front, right and top perspective view of a dosage dispenser, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an open view of portion of FIG. 1 thereof;

FIG. 10 is a folded view of portion of FIG. 1 thereof;

FIG. 11 is a front, right and top perspective view of the dosage dispenser, in use state;

FIG. 12 is a front, right and top perspective view of the dosage dispenser, in use state;

FIG. 13 is a front, right and top perspective view of the dosage dispenser, in use state; and,

FIG. 14 is a front, right and top perspective view of the dosage dispenser, in use state.

The broken lines shown in the drawings illustrate portions of the dosage dispenser that form no part of the claimed design.
